BRISGOWD

UNITED STATES PATENT OFFICE

93,314

DESIGN FOR A REFRIGERATOR CABINET

Clarence Wexelberg, Detroit, Mich., assignor, by mesne assignments, to Grunow Corporation,
Chicago, Ill., a corporation of Illinois

Application December 5, 1932, Serial No. 46,312

Term of patent 14 years

To all whom it may concern:

Be it known that I, CLARENCE WEXELBERG, a citizen of the United States, residing at Detroit, in the county of Wayne, State of Michigan, have invented a new, original, and ornamental Design for a Refrigerator Cabinet, of which the following is a specification, reference being had therein to the accompanying drawings, forming a part thereof, in which

Fig. 1 is a front elevational view of the refrigerator cabinet showing my new design.

Fig. 2 is a front perspective view thereof.

I claim:

The ornamental design for a refrigerator cabinet substantially as shown.

CLARENCE WEXELBERG.
